[57] **CLAIM**

The ornamental design for a suspended suction head for removal of free floating oil, as shown and described.

DESCRIPTION

FIG. 1 is a front perspective view of a suspended suction head for removal of free floating oil showing my new design;

FIG. 2 is a top plan view, thereof;

FIG. 3 is a front elevational view thereof;

FIG. 4 is a rear elevational view thereof;

FIG. 5 is an enlarged front elevational view of the suction head portion thereof;

FIG. 6 is a side elevational view thereof, the opposite side is a mirror image thereof;

FIG. 7 is a rear elevational view thereof;

FIG. 8 is a top plan view thereof; and

FIG. 9 is a bottom plan view thereof.

FIG. 4.

FIG. 5.

FIG. 6.

FIG. 7.

FIG. 8.

FIG. 9.
